LOUIS H. MORIN, OF NEW YORK, N. Y., AND SAM TOUR, OF ENGLEWOOD, NEW JERSEY,
ASSIGNORS TO DOEHLER DIE-CASTING CO., A CORPORATION OF NEW YORK

DIE-CASTING MACHINE

Application filed April 25, 1930. Serial No. 447,124.

This invention relates to that much-used type of die-casting machines in which the molten metal is forced into the die by means of a gaseous fluid, compressed air most commonly being employed, but the term air as used herein is intended to include any other suitable pressure fluid. This invention relates to what may be termed the furnace end of the die-casting machine, and the other parts of the complete machine, not shown in the accompanying drawings, may be of any suitable construction desired. This invention relates more particularly to die-casting machines of the kind in which the casting pot or pressure chamber is a movable ladle, and in carrying out the invention a ladle of the gooseneck type is employed. Gooseneck casting pots discharge the molten metal horizontally or vertically or at an intermediate angle through a casting nozzle, and the invention is embodied in a die-casting machine of the horizontal type, as distinguished from what is known as the vertical type.

One object of the invention is to provide improved means for connecting the movable ladle with the supply of compressed air. In carrying out this object, another object of the invention is to provide means for imparting suitable movements to the ladle. Another object is to provide improved means for locking the ladle at its casting position. Another and more general object of the invention is to provide a mechanical construction which is safe, efficient, simple, strong, durable and economical to manufacture. Other objects and advantages of the invention will hereinafter appear.

In carrying out the invention, the movable casting pot or ladle, besides having a substantially usual gooseneck casting nozzle, is provided at its top with a neck terminating in an air nozzle projecting in the same direction as the casting nozzle. The ladle has a rectilinear horizontal movement in the last part of its travel to and in the first part of its travel from its casting position, so that both of these nozzles will be seated simultaneously upon and simultaneously separated from a stationary gate nozzle for the molten metal and a stationary air-supply

nozzle respectively. Thus no movable air pipe connections, such as flexible, jointed, or sliding pipe connections, are required in the air-supply piping. A toggle is provided, the sole function of which is to lock the ladle at its casting position, the locking and the unlocking or breaking of this toggle being controlled by an operating mechanism for moving the ladle independently of this toggle. The invention further includes various features of construction and combinations of parts, as will appear from the following description.

The illustrated embodiment of the invention will now be described with reference to the accompanying drawings and thereafter the invention will be pointed out in claims.

In the drawings:

Fig. 1 is a side elevation of the furnace end of a die-casting machine embodying the invention, with the operating parts in the position they assume in the casting position of the ladle.

Fig. 2 is a central vertical section in the plane of Fig. 1;

Fig. 3 is a somewhat enlarged transverse vertical section substantially on the zig-zag line 3—3 of Fig. 1;

Fig. 4 is a plan view of the melting pot;

Fig. 5 is an enlarged view similar to Fig. 2 with parts omitted;

Fig. 6 is a plan view of the movable casting pot or ladle;

Fig. 7 is a side elevation similar to Fig. 1 but with the operating parts of the mechanism in the position they assume with the ladle at its filling position; and

Fig. 8 is a central vertical section in the plane of Fig. 7, similar to Fig. 2 but showing the operating parts in the position they take with the ladle at its filling position.

A suitable furnace 1 is provided in its upper part with a removable oblong melting pot 2 which is supported by its top flanges upon the top plate of the furnace (Figs. 2, 3, 4 and 8). The melting pot 2 is surmounted at each of its sides by side frame plates 3 and 4 which are secured to the top of the furnace. The top edge portions of these side frame plates 3 and 4 are connected together by

means of similar front and rear tie rods 5 and 6 of which the front tie rod 5 is spaced somewhat rearwardly from the front ends of these frame plates.

5 A vertical gate-providing and die-supporting plate 7 is supported upon the front ends of the side plates 3 and 4 and the front end of the furnace 1, being stationarily secured in place in the embodiment of the invention shown. Longitudinally arranged die-frame rods 8 have their ends secured to and project horizontally forward from the gate-forming plate 7, and die section 9, provided with a gate opening 10, is shown as stationarily supported on the vertical front face of this plate between these frame rods. A stationary rearwardly directed substantially cup-shaped gate nozzle 11 having a horizontal gate opening is supported by the plate 7, with the gate provided by this nozzle in communication with the die inlet 10, this gate nozzle being held in the forward reduced portion of a rearwardly flaring opening through this nozzle-carrying plate 7, as shown in the drawings.

15 A nozzle carrier 12 for the supply of compressed air is rigidly stationarily supported upon and secured to the upper portion of the vertical front plate 7 at the rear side thereof. This nozzle carrier 12 has through it an L-shaped bore forming an air passage, to the upper end of which an air-supply pipe may be connected, as indicated in the drawings. A stationary rearwardly directed cup-shaped air nozzle 13 is horizontally disposed and firmly fixed in a suitable recess in the rear face of this nozzle carrier 12. It will be noted that this air-supply nozzle 13 is spaced both above and rearwardly from the gate nozzle 11 for the molten metal, these two stationary nozzles both being directed or exposed horizontally rearwardly and being in parallel relation with one another.

20 Each of the side frame plates 3 and 4 has provided through it a front guide slot 14 and a rear guide slot 15. The front guide slot 14 comprises an upper horizontal front end portion *a*, a rearwardly and downwardly inclined portion *b* and a nearly vertical lower end portion *c*. The rear guide slot 15 comprises an upper front end portion *d* and a rearwardly and downwardly inclined portion *e*. The upper forward end portions *a* and *d* of these respective guide slots are in horizontal alignment with one another and are of equal length. The downwardly and rearwardly inclined portion *e* of the rear guide slot 15 terminates substantially at the level of the upper portion of the downwardly directed lower end portion *c* of the front guide slot 14.

25 A carrier frame for the ladle forming a cross frame between the side frame plates 3 and 4 is slidably guided by these front and rear guide slots 14 and 15. This ladle-carry-

30 ing cross frame comprises similar parallel front and rear cross rods 16 and 17 the outer ends of which are connected together by similar side bars or links 18 at the respective outer sides of the side frame plates 3 and 4 in spaced relation thereto, the front rod 16 passing through the front guide slot 14 and the rear rod 17 passing through the rear guide slot 15, so as to be slidably guided in these respective guide slots. Within each of the front guide 35 slots 14 the front cross rod 16 carries guide collars or rollers 19, while the rear cross rod 17 in the rear guide slot 15 is similarly provided with guide collars or rollers 20.

35 A gooseneck ladle 21 is rigidly but removably carried by the above described cross frame to depend therefrom between the side frame plates 3 and 4, and thus to partake of the sliding movements of this cross frame. This ladle is flattened at its sides and at its top and front is provided with a forwardly opening U-shaped hook 22 which snugly engages with the forward cross rods 16 above, below and at the rear of this rod. At its rear end and top this ladle 21 is provided with a pair of laterally spaced parallel lugs 23 which are notched as shown to fit snugly at the front of and below the rear cross rod 17. Also the sides of the ladle 21, at the rear angularly below and forwardly from the rounded bottoms of the notches provided by the parallel side lugs 23, is provided with oppositely projecting lugs 24 which are rounded on the lower sides opposite to the cross rod 17. A pair of similar clamp links 25 on this rear rod 17 at each side of the ladle 21 engage respectively around the side lugs 24. The upper rearwardly inclined end of each of these clamping links 25 is provided with a clamp screw 26 the inner ends of which engage with the rod 17 for thereby making a firm and rigid supporting connection of the rear end of the ladle 21 with this rear cross rod 17. Thus will be seen that the ladle 21 is firmly and rigidly yet removably supported upon the cross frame or carrier frame to be moved therewith.

40 At its front end and rising from its bottom the ladle 21 is provided with an upwardly and forwardly curved gooseneck 27 providing a duct which terminates at the front in a casting nozzle 28, which is a discharge nozzle for the molten metal. This casting nozzle 28 is shown as a separate removable piece of substantially usual form. In the casting position of the ladle 21, shown more particularly in Figs. 2 and 5, the nozzle 28 projects forward horizontally and has its projecting rounded tip seated in the cup formed by the above described gate nozzle 11, in position for the ejection of molten metal from the ladle 21 through these nozzles 28 and 11 into the die through its gate opening 10 shown in the die section 9.

45 An upwardly and forwardly projecting

air-conveying neck 29 connects with the top of the ladle 21 at its rear end. The lower end portion of the air passage through this neck 29 turns forwardly above a deflector 30 in the top of the ladle 21, so as to direct the stream of compressed air entering the ladle against a downwardly and rearwardly inclined baffle 31 provided on the front and upper portion of the wall of the ladle. From the top of the ladle 21 at the rear the neck 29 projects upwardly and forwardly and terminates in a forwardly projecting air inlet nozzle 32. The projecting end or tip of this nozzle 32 is rounded as shown and in the casting position of the ladle 21, shown in Figs. 2 and 5, this nozzle tip tightly fits or seats in the cup of the air-supply nozzle 13, this air-receiving nozzle 32 on the neck 29 then being in communication and in horizontal alignment with the air-supply nozzle 13, as shown. It will be noted in this connection that the air inlet nozzle 32 is spaced rearwardly and above the casting nozzle 28 to the same extent that the air-supply nozzle 13 is similarly spaced from the gate nozzle 11.

It will now be evident that as the ladle-supporting guide rods 16 and 17 move forward in the upper front horizontal aligned end portions *a* and *d* of the respective guide slots 14 and 15, the air inlet nozzle 32 will be seated against the air-supply nozzle 13 at the same time that the casting nozzle or discharge nozzle 28 for the molten metal is seated against the gate nozzle 11, with the ladle 21 then in its casting position (Figs. 2 and 5). Similarly and conversely, as the casting pot 21 is moved horizontally rearward away from its casting position, the air-receiving connection of the air inlet nozzle 32 with the air-supply nozzle 13 will be broken at the same time or simultaneously with the breaking of the connection between the discharge nozzle 28 and the gate nozzle 11. The casting nozzle 28 and the air inlet nozzle 32 provide the only openings into the ladle 21. As soon as the air inlet nozzle 32 is separated from the air-supply nozzle 13 the compressed air in the ladle 21 will be vented through this nozzle 32.

As is well understood in the art, a suitable valve device may be provided to shut off the supply of compressed air to the air-supply nozzle 13 before the above described nozzle connections are broken, and such valve device may be automatically operated, as is commonly done in automatic die-casting machines of the general type indicated in the drawings. However, the present invention is not necessarily restricted in its application to an automatic die-casting machine and could if so desired be embodied in a semi-automatic machine or in a hand operated machine, as will hereinafter clearly appear.

A pair of similar operating levers 33 are pivoted respectively at opposite sides of the

machine to rock upon stud shafts 34 which project outwardly from the lower front portions of the side frame plates 3 and 4. Each of these operating levers 33 is provided with a radial slot 35 which engages with a collar or roller 36 on the front cross rod 16 of the above described carrier frame, just inward from the end bars 18 of this frame. These operating levers 33 rock substantially through an arc of 90°, between the upright position thereof shown in Figs. 1, 2, 3 and 5, corresponding to the discharge or casting position of the ladle 21, and the rearward substantially horizontal position of these operating levers 33 shown in Figs. 7 and 8, corresponding to the filling position of the ladle 21.

It will be noted that in moving rearward and downward from their forward upright position, to their horizontal position, these slotted operating levers 33 will slidably move the front cross rod 16 of the carrier frame from the upper front ends to the lower rear ends of the front guide slots 14, while at the same time the rear cross rod 17 of the carrier frame will be slidably moved from the upper front portion to the lower rear portion of the rear guide slot 15, as shown in Figs. 7 and 8. A reverse rocking movement of these operating levers 33 will of course bring the above noted parts back to the position thereof shown in Figs. 1, 2, 3 and 5. Since the ladle 21 partakes of the movements of its carrier frame, the ladle will thus be moved back and forth between its casting position (Figs. 2, 3 and 5) and its filling position (Fig. 8).

Each of these operating levers 33 is provided with a shorter rear arm 37 to which there is pivoted the upper end of an operating link 38 which extends downward. The lower ends of these operating links 38 are pivoted respectively to the ends of operating arms 39 which rock between the substantially vertical position thereof shown in Figs. 1, 2 and 3, and the forward slightly downwardly inclined position thereof shown in Figs. 7 and 8, corresponding respectively to the casting position and to the filling position of the ladle 21. These operating arms 39 are fixed upon a transverse rocking operating shaft 40 which is journaled in bearings 41 provided on the bottom of the furnace 1 towards the front thereof, with these operating arms 39 outward from the bearings 41 at the respective sides of the furnace.

This rock shaft 40 constitutes the main operating member of the operating mechanism. In operation this main operating shaft 40 is rocked back and forth substantially through an angle of 90° between the counter-clockwise position thereof shown in Figs. 1 and 2 in which the operating arms 39 are in an upright position, and the clockwise position thereof shown in Figs. 7 and 8 in which the operating arms 39 extend forwardly or

towards the right. So far as this present invention is concerned this main operating shaft 40 could be thus rocked back and forth by means of a handle lever attached to one of its 5 ends, however the invention is shown as adapted for embodiment in an automatic die-casting machine.

In the construction shown, a crank arm 42 for rocking the operating shaft 40 is fixed on 10 this shaft intermediate of its bearings 41. This crank arm 42 projects in general in a downward direction and forms a bell-crank lever with the two operating arms 39. The rear end of a forwardly extending substantially 15 horizontal pitman 43 is pivoted to the crank arm 42, so that longitudinal back and forth substantially horizontal movement of this pitman will rock the crank arm 42, together with the main operating shaft 40. In 20 the casting position of the ladle 21 the crank arm 42 will incline downwardly and forwardly as shown in Figs. 1 and 2, while in the filling position of the ladle this crank arm will incline downwardly and rearwardly or 25 towards the left as shown in Figs. 7 and 8.

In the construction shown it will be noted that the operating shaft 40 is rocked in an opposite direction to the rocking movement which this shaft transmits through the above 30 described connections to the operating levers 33. It is to be understood of course that the pitman 43 may be operated from any convenient movable part of the complete die-casting machine, by means of connections not 35 shown, but which are well understood in the art of automatic die-casting machines. It is well known of course that all parts of the mechanism of an automatic die-casting machine are operated in proper sequence in timed 40 relation as to their movements and periods of rest, and in the case of this invention such timed operation of the pitman 43 and of a suitable valve device in control of the supply of compressed air to the air-supply nozzle 13, 45 as well as also for opening and closing the die, etc., it is to be understood may be effected by means of any suitable construction desired.

It will be noted that the above described 50 operating mechanism will slidably move the ladle 21 back and forth between its casting position and its filling position. In carrying out the invention a toggle device is provided for locking the ladle 21 at the casting position, this toggle device having no other function. 55 However, such toggle device is controlled by means which are operated by the above described operating mechanism, for maintaining the toggle in a locked condition when the ladle is at its casting position and then operating to break the toggle preparatory to the 60 movement of the ladle away from its casting position.

In the construction shown a pair of front 65 and rear toggle links 44 and 45 are provided and are pivoted together by a pivot pin 46.

The other end of the front toggle link 44 is pivoted on the rear cross rod 17 of the above described carrier frame for the ladle 21, between the parallel lugs 23 on the ladle. The other or rear end of the rear toggle link 45 is fixed upon a transverse toggle shaft 47 which is journaled in bearing blocks 48 provided in the upper rear portion of the side frame plates 3 and 4. This toggle shaft 47, it will be noted, is in horizontal alignment 70 with the aligned upper forward horizontal portions *a* and *d* of the respective front and rear guide slots 14 and 15. Thus when the toggle formed by these two links 44 and 45 is in a straightened out condition it will extend horizontally between the rear guide rod 17 of the carrier frame and the toggle shaft 47, as shown in Figs. 1 and 2 more particularly. 75

The desired dead-center position of these 80 toggle links 44 and 45 may be accurately assured by means of an adjusting screw 49 in an upper forwardly projecting end portion of the rear toggle link 45 which overlaps upon the front toggle link 44 forwardly beyond their pivot pin 46. The lower end of this screw 49 thus forms an abutment for the front toggle link 44 at the dead-center position of these links and also prevents the possibility of these links passing over and beyond, or in the present instance downward and below, the dead center on which they are to be locked. 90

Each of the bearing blocks 48 for the toggle shaft 47 is mounted for horizontal adjustment forward or back in a slotted guideway 50, respectively provided in the side frame plates 3 and 4. Such adjustment may be effected by a pair of adjusting screws 51 which are screw threaded respectively through the rear end portions of the respective side frame plates 3 and 4 and have heads rotatably engaging with the respective bearing blocks 48. This adjustment by means of these screws 51 and slideable bearing blocks 48 assures that when the toggle links 44 and 45 are in their straightened dead-center or locked position (Figs. 1, 2, 3 and 5) the casting nozzle 28 and the air inlet nozzle 32 on the ladle 21 will both be firmly held by the locked toggle respectively against the gate nozzle 11 and the stationary air-supply nozzle 13. 100

In carrying out the invention, a controlling device for this toggle is provided and is operated by the above described operating mechanism. This controlling device imparts a final locking movement to the toggle links 44 and 45, thereby to bring these links on dead center, for firmly clamping the discharge nozzle 28 to the stationary gate nozzle 11 and for similarly and at the same time firmly clamping the air inlet nozzle 32 against the stationary air-supply nozzle 13. This controlling device then holds the toggle locked 110 115 120 125 130

against breakage, with the ladle 21 thus firmly clamped at its casting position. Also this controlling device is operated to break the toggle preparatory to the moving of the ladle 21 away from its casting position, by the above described operating mechanism for the movable ladle.

In the construction shown, the rocking operating shaft 40 at one end thereof, which appears in Figs. 1 and 7 and is shown at the left in Fig. 3, has fixed thereon a two-armed cam lever 52 having a lower cam end 53 and an upper cam end 54. The operating arm 39 at this side of the machine is provided with an outwardly flat disc-like enlargement or head 55 and the cam member 52, which is flat on its inner and outer sides, is spaced outward from this head 55 by a hub on the inner side of this cam member, as shown in Fig. 3. An upwardly and somewhat rearwardly extending link 56 is provided longitudinally in its lower end portion with a guide slot 57 by which this link is slidably guided on the hub of the cam lever 52 transversely to the axis of the rock shaft 40, this link 56 being slidably guided at the front by the cam member 52 and at the rear by the head 55 of the adjacent operating arm 39.

Below its guide slot 57 the link 56 carries a cam follower roller 58 to be engaged by the lower cam end 53 of the cam lever 52 and above this guide slot 57 this link 56 carries another cam follower roller 59 to be engaged by the upper cam end 54 of the cam lever 52. The axes of the cam lever 52 and of the two cam follower rollers 58 and 59 are all in alignment. The cam lever 52 of course partakes of the above described rocking operating movement of the main operating shaft 40, through an angle of substantially 90°. This cam lever 52 will be thus rocked from its engaged or locking position shown in Figs. 1 and 3, in a clockwise direction as viewed in Fig. 1, to its disengaged position shown in Fig. 7, and then it will be rocked back again in a counter-clockwise direction from this disengaged position to its locking position shown in Figs. 1 and 3.

The upper end of the link 56 is pivoted to the end of a forwardly projecting toggle-controlling lever arm 60 which is fixed upon the projecting end of the toggle shaft 47. The link 56 is pivoted to this lever arm 60, through the intermediary of a bearing member 61 relatively to which the link 56 is longitudinally adjustable such adjustment being maintained by means of a clamp bolt 62, serrations being provided for holding the adjustment, as shown in Fig. 3. This slight longitudinal adjustment of the link 56 provides for correctly positioning its cam follower rollers 58 and 59 relatively to the cam member 52, as will be readily understood.

The two cam arms of the cam lever 52 are shown as being of the same length, although

that in itself is substantially immaterial. It will be noted, however, that each of the cam faces 53 and 54 comprises an outer arcuate portion and a depressed portion shown as concavely curved. It will be further noted that the outer arcuate portions of these two cam faces 53 and 54 are both at the same side of a diametrical line through the axis of the cam 52, and adjacent to one edge of the cam lever 52, while the depressed cam portions are at the other side of this diametrical line adjacent the other edge of the cam lever. Accordingly, a depressed portion of either of these cam faces is substantially diametrically opposite to the outer arcuate portion of the other cam face. Thus in Fig. 1, it will be noted that the outer arcuate portions of the cam faces 53 and 54 appear at the left of the cam lever 52, with the depressed cam face portions at the right.

The curve of the depressed portions of these cam faces 53 and 54 is shown as substantially the same as that of the peripheral surface of the cam follower rollers 58 and 59. The spacing apart from one another of the outer arcuate portions of the cam faces 53 and 54 is somewhat greater than the distance from one to the other between the peripheries of the cam follower rollers 58 and 59, while the diametrical distance between one of the depressed cam portions and the opposite arcuate cam portion is substantially the same as is the diametrical distance between the surfaces of the follower rollers 58 and 59. While this above noted particular construction of the locking cam 52 is not necessarily essential for carrying out the idea of the invention, it is necessary of course that the construction shown in the drawings for carrying out the invention shall be clearly understood as to its manner of operation.

In Fig. 1 the outer arcuate portion of the lower cam face 53 is shown as in engagement with the lower cam roller 58, thereby, as will be evident, locking the toggle links 44 and 45 on dead center, as shown, with the ladle 21 firmly clamped at its casting position, as shown in Figs. 2 and 5, with no possibility of the accidental breakage of the toggle while the cam 52 is held at this its locking position. This locked condition is maintained during the time that compressed air is being supplied to the air-supply nozzle 13. In this locking position of the cam lever 52 shown in Fig. 1 the upper cam roller 59 is seated in the depressed concave portion of the upper cam face 54. Immediately that the rocking operating shaft 40 starts its clockwise movement away from the position shown in Figs. 1, 2 and 3, the outer end portion of the lower cam face 53 will be moved towards the left as viewed in Fig. 1, away from and out of the path of the lower cam roller 58, while at the same time the movement towards the right of the upper cam face 54 will cause the upper cam roller 59 to

ride out of the depressed portion of this cam face and upon the outer arcuate portion thereof. As this upper cam roller 59 is thus moved upward it carries with it of course the link 56 and the lower cam roller 58, which has clearance provided for it by the recessed portion of the lower cam face 53.

When the link 56 is moved longitudinally upwardly by the upper cam face 54 as just described, this movement is transmitted through the lever arm 60 and toggle shaft 47 to the rear toggle link or toggle yoke 45, and breaks the toggle upwardly. In this connection it should be noted that each of the operating arms 39 forms a toggle with the corresponding operating link 38. In the locked clamping position of the clamping toggle formed by the links 44 and 45 shown in Figs. 1 and 2, it will be noted that these other toggles formed by the respective operating arms 39 and operating links 38 are also in a locked condition, substantially on but a little beyond their dead center. That is to say, with the ladle 21 clamped by the toggle links 44 and 45 at its casting position as shown in Fig. 2, the relationship of the respective operating arms 39 and operating links 38 is such that the pivots of these links will be respectively in substantial alignment with the axis of the rock shaft 40, but are desirably slightly out of alignment beyond their dead-center position as shown in Fig. 1.

Accordingly, during the initial portion of the clockwise rocking movement of the operating shaft 40 away from the position shown in Fig. 1, this shaft operates only to break the toggle formed by its operating arms 39 with the operating links 38, at the same time that this same movement is operating to break the toggle formed by the links 44 and 45, as above described. These toggles formed by the links 38 and operating arms 39 of course cooperate with the toggle formed by the links 44 and 45 for clamping the ladle 21 at the casting position, as well as also for locking all parts of the operating mechanism rigidly against movement, although the toggle links 44 and 45 are principally relied upon for strongly and effectively clamping the ladle 21 at its casting position.

As the rocking operating shaft 40 continues its clockwise movement, after first breaking all of the toggle connections as above described, this shaft finally reaches its other extreme position shown in Figs. 7 and 8. During this further and major part of this clockwise movement of the shaft 40, the cam lever 52 is entirely free from the cam rollers 58 and 59 and rocks idly to the nearly horizontal position of this cam lever shown in Fig. 7. Also during this same movement of the operating shaft 40 the toggle-controlling link 56 may move idly in a longitudinal direction, by reason of its guide slot 57. By a com-

parison of Figs. 1 and 7, it will be evident that this link 56 will first move in an upward direction as the toggle formed by the links 44 and 45 breaks upwardly during the first portion of the rearward movement of the rear cross rod 17 of the carrier frame, and that following this the link 56 will move idly downward to the position thereof shown in Fig. 7, as the toggle links 44 and 45 assume the position thereof shown in Fig. 8, with the ladle 21 at its rearward, lowered and tilted filling position shown in Fig. 8.

When in the sequence of the operating movements of the complete die-casting machine, the operating shaft 40 is rocked by its pitman 43 in the opposite or counter-clockwise direction, away from the position of this shaft shown in Figs. 7 and 8, the above described sliding movement of the rear cross rod 17 of the carrier frame in the rear guide slots 15 moves the front toggle link 44 so as to lift the rear toggle link 45 together with the lever arm 60. As this movement continues the toggle formed by the links 44 and 45 will be straightened out by the forward movement of the rear cross rod 17 of the carrier frame and the lever arm 60 correspondingly moved downward. The toggle-controlling link 56 idly partakes of this idle repositioning movement of the toggle formed by the links 44 and 45, this link 56 sliding first upwardly and then downwardly as it is moved by the lever arm 60.

Towards the final part of this counter-clockwise movement of the operating shaft 40, the pivotal connection of the operating arms 39 will approach a dead-center position with the operating links 38, and at this time the clamping toggle formed by the links 44 and 45 will be almost straightened out, in a close approach to its dead-center position. Substantially at this time the concave recessed portion of the lower cam end 53 of the cam lever 52 will be brought into engagement with the lower cam roller 58 on the link 56. In the final part of the continued movement of the operating shaft 40, while the operating links 38 and operating arms 39 are passing over their dead center, the movement of the cam 52 with the operating shaft 40 will cause the lower cam roller 58 to be moved downward out of the recessed portion of the lower cam face 53, so as to ride upon the outer arcuate portion of this cam face, as shown in Fig. 1, at the termination of this movement. At the same time the outer arcuate portion of the upper cam face 54 has moved beyond the upper cam roller 59 and this upper cam roller has been drawn down and seated in the recessed portion of this upper cam face, as is also shown in Fig. 1.

This downward movement imparted to the link 56 by the lower cam end 53 of the cam 52 pulls the rear toggle link 45 downward to a dead-center position with the front toggle

link 44, as shown in Figs. 1 and 2, thereby at the same time firmly clamping the discharge nozzle 28 and the air inlet nozzle 32 of the ladle 21 against the stationary gate nozzle 11 for the molten metal and against the air-supply nozzle 13 respectively, as shown in Figs. 2 and 5. The toggles formed by the operating links 38 and operating arms 39 co-operate in this clamping action. It will be noted that the movement of the operating arms 39 at their dead-center position relatively to the operating links 38 is utilized in the one instance for forcing the toggle formed by the links 44 and 45 to its dead-center position and in the other instance for breaking this toggle. It will now be clear that the only function of the toggle provided by the links 44 and 45 is for strongly clamping the ladle 21 at its casting position. Excepting in its final movement to and in its initial movement away from this clamping position, the other movements of the links 44 and 45 of this toggle are idle movements, imparted by the rear cross rod 17 of the carrier frame for the ladle 21, as above noted, as the latter is alternately moved away from and back to its casting position by the operating shaft 40, through the above described linkage connections comprised in the operating mechanism.

It will be noted that the casting pot or ladle 21 is not only moved back and forth between a casting position and a filling position, but that its movements are such when adjacent to its casting position as to be effective, in carrying out the invention, for successively alternately making and breaking the connection or communication of the ladle 21, both with the gate nozzle 11 to the die and the air-supply nozzle 13 to the ladle, the air connection thus being broken at all times except when the ladle 21 is in its discharge position. It will be noted that the last part of the movement of the ladle 21 toward its discharge position and the first part of its movement away from this discharge position toward its filling position, is in a rectilinear horizontal direction, while the cross rods 16 and 17 are being slidably guided respectively in the upper front end portions *a* of the front guide slots 14, and in the upper front end portions *d* of the rear guide slots 15.

Thereafter, as the ladle 21 continues its movement towards its filling position, it moves at an angle rearward and downward, while still being held level, that is, with its casting nozzle 28 and its air nozzle 32 still projecting horizontally, while the cross rods 16 and 17 are sliding along the rearwardly and downwardly inclined parallel portions *b* of the front guide slots 14, and *e* of the rear guide slots 15, respectively. The rear cross rod 17 continues along the inclined portions *e* of the rear guide slots 15 until it reaches or substantially reaches the ends of these slots, while as soon as the front cross rod 16 reaches

the downwardly directed lower end portions *c* of the front guide slots 14 it will be moved downward therein by the slotted operating levers 33, to or substantially to the lower ends of these guide slots, as will be clear from Figs. 7 and 8.

The carrier frame for the ladle 21 thus pivots about its rear cross rod 17, so that thereby the ladle 21 is tilted downward at its front end with its discharge nozzle 28 submerged in the molten metal in the melting pot 2, as shown in Fig. 8. This sequence of movement of the ladle 21 is of course simply reversed in the movement of the ladle from its filling position shown in Fig. 8 to its casting or discharge position shown in Figs. 2 and 5. It will be evident from the drawings, particularly from a comparison of Figs. 1 and 2 with Figs. 7 and 8, that the movements of the carrier frame, and hence of the ladle 21, are at all times positively controlled by the operating levers 33 in cooperation with the guide slots 14 and 15, without permitting any looseness or lost motion of the ladle 21.

It is obvious that various modifications may be made in the construction shown in the drawings and above particularly described, within the principle and scope of the invention as defined in the appended claims.

We claim:

1. In a die-casting machine, the combination of a melting pot, a ladle movable between filling and casting positions, means for positively slidably guiding the ladle along a fixed path throughout its movements to and away from a low position for filling and horizontally only along a rectilinear path during the last part of its movement to and the first part of its movement away from its casting position, a toggle the only function of which is for locking the ladle at its casting position, operating means for the ladle independent of the said toggle for sliding the ladle between its filling and its casting position, a locking device operated by the said operating means to prevent breakage of the said toggle in the casting position of the ladle, and a releasing device operated by the said operating means to act upon the said toggle for breaking the latter preparatory to the movement of the ladle away from its casting position.

2. In a die-casting machine, the combination of a melting pot, a ladle movable therein between a filling and a casting position, the ladle having a discharge nozzle for metal and an air inlet nozzle above the discharge nozzle and projecting in the same direction, both of these nozzles being horizontal in the casting position of the ladle, a stationary gate nozzle for the die to co-operate with the said discharge nozzle of the ladle, a stationary air-supply nozzle to co-operate with the air inlet nozzle of the ladle, and means for posi-

tively slidably guiding the ladle along a fixed path throughout its movements to include sliding movement in a horizontal direction only along a rectilinear path during the last 5 part of its movement to and the first part of its movement away from its casting position and further including sliding movement to a depressed filling position with its discharge nozzle then tilted downward in the molten 10 metal in the melting pot.

3. In a die-casting machine, the combination of a melting pot, a ladle movable therein between a filling and a casting position, the ladle having a discharge nozzle for metal and 15 an air inlet nozzle above the discharge nozzle and projecting in the same direction, both of these nozzles being horizontal in the casting position of the ladle, a stationary gate nozzle for the die to cooperate with the said 20 discharge nozzle of the ladle, a stationary air-supply nozzle to cooperate with the air inlet nozzle of the ladle, means for positively guiding the ladle along a fixed path throughout its movements to include sliding movement 25 in a horizontal direction only along a rectilinear path during the last part of its movement to and the first part of its movement away from its casting position and further including sliding movement to a de- 30 pressed filling position with its discharge nozzle then tilted downward in the molten metal in the melting pot, operating means for sliding the ladle throughout its movements between its filling and its casting position, 35 and means independent of the said operating means and operated thereby for locking the ladle at its casting position and for unlocking the ladle preparatory to its movement away from its casting position.

4. In a die-casting machine, the combination of a melting pot, a pair of vertical parallel side frames above the melting pot, a front and a rear guide slot in each side frame having horizontal front upper end portions in 40 alignment horizontally and having rear downwardly extending portions, a cross frame between the side frames and having guide members slidably guided in the respective guide slots, a ladle depending from and 45 rigidly carried by the cross frame, the ladle having a casting nozzle and an air nozzle above the casting nozzle with both of these nozzles projecting towards the front in parallel relation with the said guide members on the cross frame, a horizontal gate nozzle to 50 cooperate with the casting nozzle, a horizontal air-supply nozzle to cooperate with the air nozzle of the ladle in the casting position only of the latter, and an operating mechanism for sliding the cross frame between the 55 opposite end portions of the said guide slots thereby to move the ladle slidably between a depressed filling position and an elevated forward casting position.

5. In a die-casting machine, the combination of a melting pot, a pair of vertical parallel side frames above the melting pot, a front and a rear guide slot in each side frame having horizontal front upper end portions in alignment horizontally and having rear downwardly extending portions, a cross frame having guide members slidably guided in the respective guide slots, a ladle depending from and rigidly carried by the cross frame, an operating mechanism for sliding the cross frame between the opposite end portions of the said guide slots thereby to move the ladle slidably between a depressed filling position and an elevated forward casting position, a substantially horizontal toggle independent of the operating mechanism and having a front link pivoted to the slide- 70 able cross frame and having a rear link pivoted on the said side frames so that thereby the straightening of this toggle will lock the ladle at its casting position, means independent of but operated by said operating mechanism for locking the toggle and holding it locked in the casting position of the ladle, and means also independent of but operated by said operating mechanism for breaking the toggle to permit the ladle to be moved away from its casting position by the operating 75 mechanism.

6. In a die-casting machine, the combination of a ladle to be moved between a rearward depressed filling position and an elevated forward casting position, a substantially horizontal toggle having a forward link pivoted at its front end to the ladle and having a rear link pivoted on a stationary part so that thereby when this toggle is straightened it will lock the ladle at its casting 100 position, a main rocking operating member, a linkage connection from this operating member to the said ladle for moving the latter back and forth independently of said toggle thereby to move the ladle between its filling and casting positions, a link having at one of its ends a pivotal connection to the rear link of the toggle and at its other end being slidably guided transversely to the axis of the said main operating member, a pair of cam followers on the said link respectively 105 at opposite sides of the axis of the main operating member, and a two-faced cam carried by the said main operating member to rock therewith and having a cam face to engage with one of the cam followers to lock the said toggle against breakage in the casting position of the ladle and having another cam face to engage the other cam follower for breaking the said toggle to permit the ladle to be moved away from its casting position 110 by the rocking of the said main operating member in a reverse direction.

7. In a die-casting machine, the combination of a melting pot, a pair of side frames surmounting the melting pot, a front and a 115

- rear guide slot provided in each of the side frames, these guide slots having upper front end portions in horizontal alignment and having rearwardly and downwardly inclined portions, a carrier frame having a front and a rear guide member to slide in the respective guide slots in the side frames, a depending ladle rigidly carried by the carrier frame to be moved therewith between a rearward depressed filling position and an elevated forward casting position, a substantially horizontal toggle having a forward link pivoted at its front end to the carrier frame and having a rear link pivoted on the said side frames so that thereby when this toggle is straightened it will lock the ladle at its casting position, a main rocking operating member, a linkage connection from this operating member to the said carrier frame for sliding the latter back and forth independently of said toggle thereby to move the ladle between its filling and casting positions, a link having at one of its ends a pivotal connection to the rear link of the toggle and at its other end being slidably guided transversely to the axis of the said main operating member, a pair of cam followers on the said link respectively at opposite sides of the axis of the main operating member, and a two-faced cam carried by the said main operating member to rock therewith and having a cam face to engage with one of the cam followers to lock the said toggle against breakage in the casting position of the ladle and having another cam face to engage the other cam follower for breaking the said toggle to permit the ladle to be moved away from its casting position by the rocking of the said main operating member in a reverse direction.
8. In a die-casting machine, the combination of a ladle mounted for movement between filling and casting positions, operating mechanism for thus moving the ladle, a toggle independent of said mechanism and the sole function of which is to lock the ladle at its casting position, a controlling link connected to the toggle, means for guiding the other end of this link, a pair of cam followers spaced longitudinally on this link, and a rocking cam member between the cam followers to engage therewith to prevent the breaking of the toggle in the casting position of the ladle and to break the toggle preparatory to the movement of the ladle away from its casting position.
9. In a die-casting machine, the combination of a ladle mounted for movement between a filling and a casting position, operating mechanism for thus moving the ladle, a pair of toggle links independent of said mechanism for locking the ladle at the casting position and having no other function, and a controlling device for these toggle links operated by the said operating mechanism to maintain the toggle in a locked condition when the ladle is at its casting position and to break the toggle preparatory to the movement of the ladle away from its casting position.
10. In a die-casting machine, the combination of a melting pot, a ladle, a multi-part carrier frame for the ladle separate from and independent thereof comprising horizontal parallel front and rear cross rods to which the ladle is rigidly but detachably secured and separable side bars detachably connecting the said cross rods together thereby to form the said carrier frame, and a pair of side frames surmounting the melting pot and between which the cross rods extend and each of which is provided with a front and a rear guide slot in which the said cross rods of the carrier frame are respectively guided for sliding movement.
11. The invention defined in claim 4, in which the said rear downwardly extending portions of the said front and rear guide slots comprise rearwardly and downwardly inclined parallel portions which in the front guide slot opens into a further downwardly extending lower end portion which terminates at a lower level than the lower end of the said rear guide slot.
12. The invention defined in claim 4, in which the said rear downwardly extending portions of the said front and rear guide slots comprise rearwardly and downwardly inclined parallel portions which in the front guide slot opens into a further downwardly extending lower end portion which terminates at a lower level than the lower end of the said rear guide slot, and in which the said operating mechanism includes a pair of rocking operating levers connected to the said cross frame adjacent to the point where the latter is guided in the said front guide slots and mounted to rock between an upstanding position with the ladle at its casting position and a rearwardly extending position with the ladle at its filling position.
13. The invention defined in claim 10, in combination with an operating mechanism for the ladle including a pair of rocking operating levers connected to the respective end portions of one of said cross rods of the carrier frame and mounted to rock between an upstanding position with the ladle at its casting position and a rearwardly extending position with the ladle at its filling position.
14. The invention defined in claim 10, in which said side bars connect said cross rods together at the outer sides of said side frames in outwardly spaced relation from the side frames, in combination with an operating mechanism for slidably moving the ladle between an elevated forward casting position and a depressed filling position including a pair of rocking operating levers having a combined longitudinally slidable and

pivotal connection respectively with the front cross rod of the carrier frame in the space between the side bar and side frame and mounted to rock between an upstanding position with the ladle at its casting position and a rearwardly extending position with the ladle at its filling position.

15. In a die-casting machine, the combination of a melting pot, a pair of vertical parallel side frames above the melting pot, each of said side frames being provided with a front and a rear guide slot having horizontal front upper end portions and rear downwardly extending portions, a cross frame between the side frames and having guide members slidably guided in the respective guide slots, a ladle depending from and rigidly carried by the cross frame, the ladle having a casting nozzle projecting towards the front in parallel relation with the said guide members on the cross frame, and an operating mechanism for the ladle including a pair of rocking operating levers connected to the said cross frame adjacent to the respective side frames and mounted to rock between an upstanding position with the ladle at an elevated forward casting position and a rearwardly extending position of said levers with the ladle at a depressed filling position.

16. In a die-casting machine, the combination of a melting pot, a pair of vertical parallel side frames above the melting pot, each of said side frames being provided with a front and a rear guide slot having horizontal front upper end portions and rearwardly and downwardly inclined parallel rear portions which in each of said front guide slots open into a further downwardly extending lower end portion, a cross frame between the side frames having guide members slidably guided in the respective guide slots, a ladle depending from and rigidly carried by the cross frame, the ladle having a casting nozzle projecting towards the front in parallel relation with the said guide members on the cross frame, and an operating mechanism for sliding the cross frame between the opposite end portions of the said guide slots thereby to move the ladle slidably between a depressed filling position with its casting nozzle tilted downward in the molten metal in the melting pot and an elevated forward casting position.

55. In witness whereof, we hereunto subscribe our signatures.

LOUIS H. MORIN.
SAM TOUR.
